[57] CLAIM

The ornamental design for an electrically actuated valve, as shown and described.

DESCRIPTION

FIG. 1 is a top, front and right side perspective view of an electrically actuated valve showing my new design; and,

FIG. 2 is a bottom, rear and right side perspective view thereof, the left side being a mirror image of the right side.

The broken line representation of an electric line and switch in FIGS. 1 and 2 is for purposes of illustration only and forms no part of the claimed design.

FIG. 1

FIG. 2
